UNITED STATES PATENT OFFICE.

ROBERT H. BEAUMONT, OF RADNOR, PENNSYLVANIA, ASSIGNOR TO R. H. BEAUMONT CO., OF PHILADELPHIA, PENNSYLVANIA, A CORPORATION OF PENNSYLVANIA.

HOISTING APPARATUS.

Application filed May 4, 1926. Serial No. 106,600.

This invention relates to apparatus generally useful in hoisting material such as sand, gravel, coal, ashes, etc., and more particularly to a type in which a skip bucket is employed as a means to convey the material to the desired levels for gravity dumping into cars, bins or other receptacles.

In hoisting systems of the kind specifically referred to, it has been necessary heretofore to employ double, and in some instances, triple rails to guide travel of the skip buckets, as well as more or less complicated switch mechanism to divert the buckets temporarily from the main rails to lateral auxiliary rails for the purpose of inversion and dumping at the desired discharge levels. Accordingly, such systems were very expensive to construct and install; and, furthermore, involved considerable outlay for maintenance due to requirement for extensive lubrication of the numerous rails and associated switches.

The present invention is directed toward overcoming the various drawbacks above mentioned; or, in other words, toward enabling accomplishment of the desired functions with a less expensive organization permitting use of a pair of single rails to guide travel of the skip buckets from the point of loading to the point of delivery, and a very simple means to effect automatic inversion of the buckets for dumping at the discharge levels.

The advantages of this invention will be apparent from the following description of the typical embodiment shown in the drawings, whereof Fig. I shows a fragmentary portion of my novel hoisting system in side elevation.

Fig. II is a rear elevation viewed as indicated by the arrows II-II in Fig. I.

Figs. III, IV and V are local detail sectional views taken as indicated respectively by the arrows III-III, IV-IV, and V-V in Fig. I.

Referring more in detail to these illustrations, the numeral 10 comprehensively designates a skip bucket which is characterized by a sloping mouth 11 at the top, the whole being constructed from sheet metal with appropriate structural iron bracing to provide the necessary strength and rigidity after customary practice. This skip bucket 10 is actuated by hoisting gear which includes a carriage 12 having a cross bar 13 at

the top whereto is pivotally attached, at the center, a counterweighted sheave 14 to take into the loop of a tow cable 15 capable of being actuated by suitable winding mechanism, not shown. The carriage 12 is confined to travel along a guide track 16 herein shown as inclined to about 60 degrees, but which may take any angle between the vertical and horizontal to suit special considerations of practice. From Fig. II it will be noted that the track 16 comprises a pair of single rails 17, 17 which may be of any standard cross section, angle bars such as shown in the present instance, being employed for the sake of economy and structural lightness. In order to be held to the rails 17, 17 the carriage 12 is equipped top and bottom with wheels 18, 18 and 19, 19 respectively, that are arranged in pairs—as shown in Figs. I and III—to engage opposite sides of the inwardly directed lateral flanges of said rails. The outer set 19 of the wheels is common to both the carriage 12 and the bucket 10, by virtue of being mounted upon a shaft 20 with which said bucket has pivotal connection at 21, 21 (Fig. II) for dumping, as hereinafter fully explained. In order to normally restrain the bucket 10 against movement about the shaft 20, I provide it at each side of its upper end, with wheels 22, 23 which, like the wheels of the carriage 12, engage opposite sides of the flanges of the rails 17, 17. It is to be particularly noted that the wheels 23 are of substantially the same width as the rail flanges, while the wheels 22 are considerably narrower for capacity to pass through cut outs or recessions 24 in the guide flanges of the rails 17 at the dumping level, where lateral rail offsets 25 are installed for the purpose of supporting the wheels 23 while the lower wheels 19 continue in their travel upward along the track 16, to bring about inversion of the bucket 10 on the shaft 20 of the carriage 12, as shown in dot-and-dash lines at the top left hand of Fig. I. From Fig. IV it will be observed that the horizontal offset rails 25 are in the form of plates which are secured, at the inner ends, to channel sections 26, in turn secured along portions of the main rails 17.

Suitable spacing blocks 27 are employed at the junctures to bring the offset rails 25 into a vertical plane midway of the active flanges of the main rails 17.

At the back, the skip bucket 10 carries a

pair of straps 28 which are preferably fashioned from stout bar metal to the configuration shown in Fig. I for capacity to serve as cams in cooperation with fixed abutment 5 stops having the form of rollers 29 which are carried by a bracket frame 30 bridging over the track 16. These rollers 29 are so allocated as to engage the cams 28 just as the upper wheels 23 of the bucket 10 approach the 10 dumping level. As a consequence of such engagement, the upper end of the bucket 10 is displaced inward so that its wheels 22 are diverted to pass through cut outs 24 of the main track rails 17 and onto the offset rails 25. 15 The dumping action is thus effected automatically incidental to upward travel of the carriage 12 along the main track rails 17. In order to limit the tilt of the bucket 10 in the event of excess upward travel during 20 dumping, I provide it with hooked tail projections 31 adapted to engage with the side bars of the carriage 12 in the manner indicated in Fig. I.

Return of the bucket 10 to normal position 25 after dumping is facilitated by guards 32 associated with the auxiliary offset rails 25, said guards being outwardly curved—as shown in Fig. V—to centralize the wheels 23 relative to the track 16 in a manner obvious 30 from the illustration last referred to.

The described organization is manifestly simple both with regard to construction and operation, and, by reason of its simplicity, easy as well as inexpensive to install and maintain as compared with hoisting systems heretofore existent.

Having thus described my invention, I claim:

1. In hoisting apparatus of the character described, a skip bucket with companion pairs of upper and lower wheels, a track with which all of said wheels normally engage to guide travel of the bucket, and means co-operative with a fixed abutment bridging the track to forwardly displace the upper pair of wheels temporarily from said track and thereby effect non-gravitational inversion of said bucket for dumping about the axis of one of the lower pairs of wheels incidental to continued 50 travel of the latter along the track.

2. In hoisting apparatus of the character described a skip bucket with companion pairs of upper and lower wheels, a track with which all of said wheels normally engage to guide travel of the bucket, a cam on the back of the bucket adapted to engage a fixed abutment in the path of travel to forwardly displace the upper pair of wheels from the rails and thereby effect positive non-gravitational inversion 55 of said bucket for dumping about the axis of one of its lower pair of wheels incidental to continued travel of the latter along the track.

3. In hoisting apparatus of the character described, a skip bucket with companion pairs of upper and lower wheels, a pair of track

rails having lateral flanges with the opposite faces of which said wheels normally engage to guide travel of the bucket, cam means on the bucket co-operative with stationary abutments to effect displacement of the upper 70 pairs of wheels temporarily from the rail flanges and thereby permit non-gravitational inversion of said bucket for dumping about the axis of a pair of its lower wheels incidental to continued travel of the latter along 75 the track, and means to limit turning movement of the bucket during dumping.

4. In hoisting apparatus of the character described, a skip bucket with companion pairs of upper and lower wheels, lifting gear affording the bucket pivotal connection on the axis of opposed lower wheels, a pair of single track rails having lateral flanges with which all of said wheels normally engage to guide travel of the bucket, said rails having offsets 80 for dumping, and cam means on the bucket co-operative with stationary abutments to effect displacement of its upper companion wheels sidewise from the track rails so that the lower ones thereof engage the offsets for support during non-gravitational inversion of 85 said bucket incidental to continued travel of the lower wheels along the track rails aforesaid.

5. In hoisting apparatus of the character described, a skip bucket with companion pairs of upper and lower wheels, lifting gear affording the bucket pivotal connection on the common axis of a pair of lower wheels, a pair of single track rails having lateral flanges 90 for the wheels aforesaid to guide travel of the bucket, said rails having horizontal offsets for dumping, cam paths on the bucket co-operate with rollers carried by a rigid bridge spanning the track to effect displacement of 95 its upper companion pairs of wheels sidewise from the track so that the lower ones thereof traverse the horizontal offsets for support during non-gravitational inversion of said 100 bucket incidental to continued travel of the lower wheels along the track, and means co-operating with the lifting gear aforesaid to limit turning movement of the bucket during 105 dumping.

6. In hoisting apparatus of the character described, a skip bucket, a carriage affording the bucket pivotal connection at the lower end, a pair of single track rails having lateral flanges to guide travel of the carriage aforesaid, companion pairs of rollers on the upper end of the bucket normally running on said rails, and a stationary abutment bridging the track and co-operative with cam paths on the bucket to effect displacement of its upper 110 companion wheels from the rails onto horizontal offsets for inversion about the pivotal connection with the carriage and dumping 115 of its contents.

7. In hoisting apparatus of the character described, a skip bucket, a carriage having 120

companion pairs of rollers at its lower end, one set of rollers having a common axis affording the bucket pivotal connection at said lower end, a pair of single track rails to guide travel of the carriage aforesaid, companion pairs of rollers on the upper end of the bucket normally running on said rails, freely revolvable rollers carried by a bracket frame bridging the track rails, and cam paths on 10 the bucket co-operative with said rollers to

effect displacement of its upper companion wheels laterally through cut outs in said rails onto horizontal offsets for inversion of the bucket about the common axis of the carriage aforesaid and dumping its contents. 15

In testimony whereof, I have hereunto signed my name at Philadelphia, Pennsylvania, this 29th day of April, 1926.

ROBERT H. BEAUMONT.
